DESIGN FOR A COMBINED JAR AND BOTTLE WRENCH

Bertis F. Hamilton, Columbus, Ind.

Application August 21, 1936, Serial No. 64,503

Term of patent 3½ years

To all whom it may concern:

Be it known that I, Bertis F. Hamilton, a citizen of the United States, residing at Columbus, Bartholomew County, Indiana, have invented a new, original, and ornamental Design for a Combined Jar and Bottle Wrench, of which the following is a specification, reference being had to the accompanying drawing, forming part thereof.

Fig. 1 is a plan view of a wrench embodying my design; Fig. 2 is a side elevation of the wrench of Fig. 1; and Fig. 3 is a section on the line 3—3 of Fig. 1.

I claim:

The ornamental design for a combined jar and bottle wrench, as shown.

BERTIS F. HAMILTON.
